BLOOD FILTER

David J. Rosenberg, 12 Francis Court,
Glen Cove, N.Y. 11542

Filed June 16, 1972, Ser. No. 263,494

Term of patent 14 years

Int. Cl. D24—02

U.S. CL. D83—1 R

FIG. 1

FIG. 2

FIG. 3

FIG. 1 is a top plan view of a blood filter showing my new design, the bottom being the same as the top shown;

FIG. 2 is a side elevational view thereof, the opposite side being the same as the side shown; and

FIG. 3 is an end elevational view thereof, the opposite end being the same as the end shown.

I claim:

The ornamental design for a blood filter, substantially as shown and described.
